G. J. Lowell, of Philadelphia, Penna.

Letters Patent No. 2190 Dated Oct. 10, 1865.

Design for a Clock Front.

The schedule referred to in these letters patent and making part of the same.

To all whom it may concern:

Be it known that G. J. Lowell, of Philadelphia, City of Philadelphia, State of Pennsylvania, have invented or produced a new and original design for a clock front, and I do hereby declare the accompanying drawing with the following explanation of the same, to form a full, clear and exact description of the said design.

My design relates to the shape and configuration of the front frame or door of a clock case, this frame consisting of the base piece A, the two uprights B and B', cross-pieces F and F' and diagonals C and H, joined together and arranged in respect to each other as illustrated in the accompanying drawing.

The upper space of the clock front is of such dimensions that the dial of the clock can be seen through it.

Each end of each of the pieces composing the clock front, projects beyond that to which it is secured, as is illustrated in the drawing, so that the whole may present a rustic appearance.

Claims

The shape and configuration of the clock front substantially as represented in and by the accompanying drawing.

In testimony whereof I have signed my name to this specification in the presence of two subscribing witnesses.
